UNITED STATES PATENT OFFICE.

MARTIN HANSON, OF CHICAGO, ILLINOIS, ASSIGNOR TO LOUIS HANSON COMPANY, OF CHICAGO, ILLINOIS, A CORPORATION OF ILLINOIS.

HYDRAULIC CHAIR.

977,736.

Specification of Letters Patent.

Patented Dec. 6, 1910.

Application filed July 9, 1910. Serial No. 571,145.

To all whom it may concern:

Be it known that I, MARTIN HANSON, a citizen of the United States, residing at Chicago, county of Cook, and State of Illinois, have invented certain new and useful Improvements in Hydraulic Chairs, of which the following is a specification, reference being had to the accompanying drawings, forming a part thereof.

10 The purpose of this invention is to provide an improved construction in hydraulic chairs.

It consists of features of construction shown and described as indicated in the 15 claims.

In the drawings—Figure 1 is an axial section of the standard of a chair embodying this invention. Fig. 2 is a section at the line 2—2 on Fig. 1. Fig. 3 is a section at the line 20 3—3 on Fig. 1.

A portion of this invention relates to the valve structure of the hydraulic chair illustrated. This will be first described.

1 is the standard or chair, within which 25 the chair stem 2 is fitted for reciprocation pistonwise, said chair stem being itself a hollow cylinder having reciprocating within it the piston 3, which is operated by connections, which need not be further described, for pumping the oil or other liquid 30 with which the standard is filled, for operating the chair in a manner well understood. The lower end of the chair stem (which is substantially the pump-barrel) is fitted with 35 a downwardly-opening, upwardly-seating check valve 4, held normally seated upwardly by a spring 4^a for opening downwardly to permit the oil to be forced down through the bottom of the pump-barrel chair stem, into 40 the cavity of the standard, this being the means by which the chair is elevated, as well understood.

The piston-valve device is constructed for 45 performing two functions: First, the ordinary function of a piston valve,—that is, of opening upwardly to permit the liquid to pass up through the piston when the latter is forced downward for forcing the liquid out past the valve 4; and second, the function of 50 opening to permit the liquid to pass upward through the piston when the valve 4 is also opened, so that the liquid can escape from below the stem to permit the chair to descend. For the purpose of these two functions, the valve device in the piston 3 com-

prises a valve-seating element 5, which is permanently secured in the bottom of the piston, and has passage through it for the movement of the liquid from one side to the other of the piston, terminating at the lower 60 side of said valve-seating element in a port 6, which is closed by the upwardly seating valve 7 (hereinafter referred to as "the main valve"), said passage terminating at the upper side in a plurality of ports, one of 65 which is occupied by the stem of the valve 7, which fits into and closes said port, except in so far as passage is afforded through said port by the axial aperture 8, which extends through said valve 7 and its stem, from end 70 to end. In the structure shown in the drawings, the remaining portage or passage through the valve seat 5 consists of the circular group of ports 9, 9, which are arranged in a circle about the central port and stem of 75 the valve 7. The upper end of the aperture 8, through the valve 7 and its stem 7^a, is provided with a valve 10 (herein referred to as a "supplemental valve"), having a stem 11, which extends through the axial aperture 8, 80 and at its lower end has coiled about it a relatively heavy spring 12, reacting between the lower end of the valve 7 and a stop nut 13, screwed onto the end of the stem 11, such spring operating by relatively strong tension 85 to hold the valve 10 seated upon the upper end of the stem of the valve 7, and causing the two valves to move as a unitary structure except under conditions causing the compression of the spring 12, as will be hereinafter 90 explained. A relatively light spring 14 reacts between the valve 10,—which has a flange 10^a at its upper end for seating the spring,—and the upper end of the valve-seating element 5. Such spring, it will be 95 seen, acts to seat the valve 7 lightly, according to the tension of the spring 14.

Upon consideration of this structure, it will be seen that in the ordinary pumping action, the springs 4^a and 14 will yield to 100 permit the valves which they respectively control,—viz: the valves 4 and 7,—to open in the ordinary manner of pump valves, for passing the liquid down into the chamber below the valve 4, and this will occur in the 105 case of any stroke of the piston which is not so deep as to cause the lower end of the stem 11 of the valve 10 to force the valve 4 down to the limit of its stroke, so as to meet with the positive resistance afforded by the rigid 110

- bottom of the pump-barrel chair-stem, which, in the further downward movement of the piston, will cause the valve 10 to be opened, while the valve 10 will be also held open by 5 the stem 11 encountering the stem of the valve 4. Such deeper stroke of the piston will be given by the operator when it is desired to permit the chair to descend, because, by such deeper stroke, holding open both the 10 valve 4 and the valve 10, a free passage upward will be provided for the liquid, which will be forced out of the chamber under the chair stem by the weight of the descending chair.
- 15 The means for reciprocating the piston, shown, comprises the rock shaft 15, having a short crank 16, connected by a pitman 17 with the stem 18 of the piston 3, and it will be seen that any means provided for rocking 20 the shaft 15 may be operated either for giving the piston a short stroke, insufficient for forcing up the valve 10, or the full length stroke for opening said valve.

I claim:

- 25 1. In a hydraulic chair, a valve device for the purpose indicated, consisting of a valve-seating element through which the flow of liquid is to be controlled, the liquid passage therethrough opening at one end of said element in a single port and at the other end in a plurality of ports; a main valve which closes the single port having a stem which extends through one of the ports at the other end, said main valve and stem being aper- 30 tured from end to end; a supplemental valve which closes said aperture of the main valve stem; a relatively strong spring which reacts between the two valves for holding the supplemental valve seated, and a relatively 35 light spring which reacts between said supplemental valve and said valve-seating element for holding the main valve seated.
2. In a hydraulic chair, a valve device for the purpose indicated, consisting of a seat- 40 ing element through which the flow of liquid is to be controlled; a liquid passage there-

through opening by a single port at one end and by a plurality of ports at the other end; a main valve which closes the single port having a stem which occupies one of said 50 plurality of ports, said main valve and its stem being axially apertured from end to end; a supplemental valve which closes the end of said axial aperture in the main valve stem, having a stem which extends through 55 said axial aperture and protrudes below the main valve stem; a stop on the protruding end of said stem; a relatively strong spring reacting between said stop and the main valve for holding the supplemental valve 60 seated; and a relatively light spring reacting between the supplemental valve and said valve-seating element.

3. In a hydraulic chair, a valve device for the purpose indicated, consisting of a valve- 65 seating element through which the flow of liquid is to be controlled, having for such flow a passage which at the lower end opens by a single port, and at the upper end opens by a central port and a group of ports sur- 70 rounding such central port; a main valve which closes said single port, having its stem occupying said central port, said main valve and its stem being axially apertured from end to end; a supplemental valve which 75 closes the upper end of said axial aperture, having a stem which extends down through said aperture and protrudes below the same; a stop in said stem, and a relatively strong spring reacting between said stop and the 80 lower end of the main valve for holding the supplemental valve seated, and a relatively light spring reacting between the supplemental valve and the upper end of the valve- 85 seating element.

In testimony whereof, I have hereunto set my hand, at Chicago, Illinois, this 6th day of July 1910.

MARTIN HANSON.
